INVENTOR :

Mitchell Leventhal

By Attorney

Abraham Engel.

UNITED STATES PATENT OFFICE.

MITCHELL LEVENTHAL, OF BROOKLYN, NEW YORK, ASSIGNOR TO SOSY, INC., OF NEW YORK, N. Y., A CORPORATION OF NEW YORK.

LOCK.

Application filed June 16, 1928. Serial No. 285,843.

The present invention relates to locks, and more particularly to suit-case locks of the spring pressed draw-bolt type, and aims to provide certain improvements therein.

Heretofore in locks of the type to which the present invention relates the lock mechanism at the rear of the cover plate was of substantial thickness which necessitated grooving or cutting an opening in the member to which the lock was fitted in order to accommodate said lock mechanism. To avoid this grooving or cutting operation it had been heretofore proposed to form the cover plate with a deep flange about its perimeter to completely house the lock mechanism, but this practice was found objectionable because it rendered the lock too thick and unsightly.

According to the present invention I provide a lock wherein the lock mechanism at the rear of the cover plate contains not more than two superposed thicknesses of material, which double thickness is of less depth than that of the cover plate flange. In this manner all need for grooving and cutting away of the lock receiving member is obviated.

According to the present invention I provide a lock of the type described which is exceedingly simple and sturdy in construction and which admirably lends itself to mass production. The invention also contemplates and embodies other features of novelty which will be hereinafter more fully described.

A preferred embodiment of my invention is illustrated in the accompanying drawings, wherein:

Figure 1 is a top plan view of a lock embodying my invention.

Fig. 2 is a bottom plan view of the lock.

Fig. 3 is an enlarged longitudinal section taken substantially along the plane of the line 3-3 of Fig. 2.

Fig. 4 is a section taken substantially along the planes of the line 4-4 of Fig. 3.

Fig. 5 is a top plan view of the draw-bolt.

Fig. 6 is a section substantially along the planes of the line 6-6 of Fig. 5.

Fig. 7 is a perspective view of the tumbler. 50

Referring to the drawings, let A indicate the lock as a whole and B any form of hasp adapted to be used therewith. The lock A may be said to consist of the following principal elements: a cover plate C, a draw-bolt 55 D, a tumbler E, a rear plate F and an escutcheon G.

The cover plate C may be of any size and outline and is preferably of substantially flat form provided about its perimeter with a rearwardly directed continuous flange c. In its face it is provided with a hasp opening c', a second opening c² and corner openings c³ through which rivets for securing the lock upon a supporting member may be passed. 65

The draw-bolt D is preferably formed from a flat piece of metal and is adapted to slide against the back of the cover plate. In outline it is substantially of rectangular form and is provided at one edge with a centrally projecting tongue d. Within its body portion it is provided with a recess d' for accommodating the tumbler E and within which said tumbler is adapted for limited movement. One edge of the recess d' is provided with a cam projection d² adapted for cooperative engagement with a cam face e on the tumbler E. To the left of the recess d' the draw-bolt is provided with a raised or struck-up substantially circular portion 70

d³ having a central opening d⁴ therein. The function of said struck-up portion d³ and opening d⁴ is to accommodate the end of a key H and provide a stop for cooperation with the bit of the key to limit its insertion 75 into the lock. The draw-bolt D is also provided with a pair of longitudinally extending openings d⁵ through which depending lips or lugs g on the opposite sides of the escutcheon G extend and have their protruding ends twisted, as best shown in Figs. 2 and 4, so as to prevent separation of said members. In this manner the escutcheon G is carried by the draw-bolt D and is movable therewith as a unit. For normally urging 80

the draw-bolt into latching position a flat spring d⁶ having one end thereof fixed in a recess in the draw-bolt is provided, which 85

spring in the assembled lock abuts against a shoulder f on the rear plate F . Obviously any other form of spring or other method of holding the same may be substituted for that just described.

The tumbler E as herein shown is formed of a flat piece of metal of substantially the same thickness as that of the draw-bolt and is positioned within the recess d' in the draw-bolt to lie within the face planes thereof. As previously stated, said tumbler is provided with a cam surface e for cooperative engagement with a cam d^2 . For holding said cam surfaces on the tumbler and on the draw-bolt in engagement, the tumbler is provided with a flat spring e' held in substantially the same manner as the spring d^6 or in any other manner, the spring engaging against one edge of the recess and being held under compression. At one end the tumbler is formed with a recess or rabbet e^2 for cooperative engagement with an abutment f' struck-up from the face of the rear plate F and projecting into one corner of the recess d' . For moving the tumbler into and out of locking engagement with said abutment f' , the tumbler is formed at one edge with a V-shaped recess e^3 in which the bit h of the key H is adapted to engage, rotary movement of the key being capable of moving the tumbler to the right or left. For providing a clearance for the bit h during its turning movement the cover plate is bent outwardly as best shown at c^4 in Fig. 3. The rear plate F fits within the flanged perimeter of the cover plate and has a flat portion f^2 which seats flush against the back of said cover plate and a central substantially rectangular raised or struck-up portion f^3 , the inner side walls of which are adapted to guide, and the inner end walls of which limit the movement of the draw-bolt D . The end wall of the struck-up portion which overlies the tongue d is cut away to accommodate said tongue and provide a guide therefor. The depth of said struck-up portion is just sufficient to clear the top faces of the draw-bolt and the tumbler and thus maintain them in proper operative position. The free end of the spring d^6 abuts against the wall f of the struck-up portion and being under compression normally urges the draw-bolt into latching position.

The rear plate F is provided in its portion f^2 with two openings f^4 and f^5 , the former serving for the insertion of a suitable tool for engaging the spring d^6 to move it into place, and the latter being a clearance opening at the rear of opening c' for permitting movement of the tongue d and the reception of the tongue engaging element of the hasp (not shown). In order to avoid an additional thickness of metal at the rear of the cover plate the struck-up portion of the rear plate is formed with an opening f^6

through which the struck-up portion d^3 and the twisted lugs g extend. The rear plate F has an outline which insures it against lateral movement with respect to the cover plate and it is held flush against the back of said cover plate through the medium of lips c^5 bent down thereover, said lips being integral with the flange c .

The escutcheon G may be of any desired configuration and is preferably in the form of a stamped or drawn boxing having an outline similar to that of the cover plate C adapted to provide a suitable finger engagement for moving the draw-bolt rearwardly against the tension of spring d^6 . It is of a size to provide a closing for the opening c^2 in the cover plate and has its inner edges seating against the outer face of the cover plate and slideable thereon through a range limited by the range of movement of the draw-bolt. As is conventional the escutcheon is provided with a key opening g^2 to accommodate the key H .

While I have shown and described a preferred embodiment of my invention it will be understood that I do not wish to be limited to the specific details of construction disclosed, since various modifications thereof may be resorted to without departing from the spirit of the invention.

What I claim is:

1. A lock comprising a flat draw-bolt having a recess therein, a tumbler within said recess, said tumbler and draw-bolt having cooperating cam surfaces, and spring means acting to hold said parts with their cam surfaces in engagement.

2. A lock comprising a cover plate, a flat draw-bolt having a recess therein slideable against the back of the cover plate, a flat tumbler within said recess, said tumbler and draw-bolt having cooperating cam surfaces, spring means acting to hold said cam surfaces in engagement, a rear plate which together with the cover plate provide a housing and guide for the draw-bolt, a spring acting upon said draw-bolt urging it into latching position and an abutment on the housing extending into the recess in the draw-bolt adapted to cooperate with the tumbler to lock the draw-bolt in latching position.

3. A lock comprising a cover plate, a flat draw-bolt, a flat tumbler lying within the face planes of the draw-bolt, the draw-bolt and the tumbler being slideable as a unit against the back of the cover plate, and a rear plate having a portion lying against the back of the cover plate and a portion raised to engage over the draw-bolt and the tumbler to hold said parts in operative position.

4. A lock comprising a cover plate, a flat draw-bolt, a flat tumbler lying within the face planes of the draw-bolt, the draw-bolt and the tumbler being slideable against the

back of the cover plate, a fixedly held rear plate seating against the back of the cover plate having a recess encompassing the draw-bolt and providing a guide and limiting shoulders therefor, a spring between one of said shoulders and the draw-bolt normally urging the tongue of the latter into latching position, and means on the rear plate overlying the draw-bolt and the tumbler to hold said parts in sliding contact with the back 10 of the cover plate.

In witness whereof, I have hereunto signed my name.

MITCHELL LEVENTHAL.
